K. P. McElroy

UNITED STATES PATENT OFFICE.

EDWARD N. STONE, OF OGDEN, UTAH, ASSIGNOR OF ONE-HALF TO CRESSON-MORRIS COMPANY, OF PHILADELPHIA, PENNSYLVANIA, A CORPORATION OF PENNSYLVANIA.

SCREEN WALL FOR CENTRIFUGAL BASKETS.

Application filed March 21, 1923. Serial No. 626,582.

This invention relates to screen walls for centrifugal baskets and it comprises a metallic foraminous sheet provided near one end with a plurality of slots and near the other end with a plurality of corresponding struck out inwardly projecting fingers which, advantageously, in turn are provided with struck out tanks or lips whereby the sheet may be bent into annular form and the ends 10 connected by lapping the fingered end under the slotted end with the fingers in the slots and the struck out lips, when used, bent backward to prevent accidental removal of the fingers from the slots; all as more fully 15 hereinafter set forth and as claimed.

The wall of basket centrifugals is usually composed of slotted or perforated metal or a wire mesh material which in use is supported in basket centrifugals at the top and 20 bottom. In use this wall is the part most subject to wear and the part needing the most frequent repair or replacement. Usually in placing or replacing the basket wall a flat sheet of suitable perforated or foraminous metal is bent into annular form and the ends of the sheet riveted, soldered or 25 clamped together. This operation requires considerable time, skill and labor.

Among other objects of the present invention is the provision of a screen wall which can be cut into standard lengths at the factory and shipped, stored and handled in flat or arcuate form and after positioning in the centrifugal can have the ends readily 30 secured in locking engagement with a minimum of time, labor and skill; and the provision of locking means for a screen wall permitting ready disengagement. To this end I make a screen wall of suitable length 35 and size provided at one end with a plurality of inwardly projecting stamped out fingers, each finger on its upper face having a struck out tang or lip and provided adjacent the other end of the screen with a corresponding number of transverse slots of a width 40 corresponding to the fingers. This construction permits bending the sheet into annular form with the end upon which the fingers are struck out underlapping the slotted 45 end with insertion of the fingers in the slots and retention of them therein by means of the struck-out tangs or lips. This construction results in engagement strong 50 enough to withstand the heavy stresses and

strains incident to the use of a centrifugal 55 and results in a wall having substantially smooth inner surfaces which presents no sharp edges or angles and which permits easy and ready scraping by the plow or other instrument used for discharging and removing 60 the solid material from the screen wall.

The screen wall may be made of one standard length of metallic screen and in use its ends may be locked by the means described. Or the screen may be made of a number of 65 standard sections each united to the adjoining sections by means of the described tongues and slots. When a wall made up of a plurality of sections is used, one worn or damaged section may be replaced with 70 a minimum expenditure of time and labor.

Centrifugal walls under the present invention are useful for screens or baskets of machines used in the centrifugal separation and straining of material of any kind, but they 75 are particularly useful in machines used for the separation and purification of sugar.

In the accompanying drawings showing one form of a specific embodiment of my invention and in the several views of which 80 similar reference numerals designate corresponding parts, Fig. 1 is a face view of the screen before it is bent into annular form;

Fig. 2 is an outer face view of the two ends secured together when the sheet is bent 85 into annular form;

Fig. 3 is an inner face view of the two ends secured together and

Fig. 4 is a transverse sectional view on an exaggerated scale on line 4—4 of Fig. 2. 90

Referring to the drawings 1 indicates a sheet of metal suitable for use as a screen in a centrifugal basket. This sheet is of foraminous material but it is here shown plain for simplicity of illustration. This 95 sheet adjacent one end is provided with a series of transverse slots 2 and adjacent the other end it is provided with a plurality of fingers 3. These fingers are made by stamping out the metal in the form shown. When the sheet is bent into annular form its ends overlap and the fingers 3 are passed through the corresponding slots 2. In use the stresses to which a machine of this type is subject are all directed outward from the center 100 and the tendency of the ends of the sheet to pull away from one another serves to hold the fingers tightly in the slots. Additional 105

means for preventing unintentional or accidental escape of the fingers from their slots may be provided. Some or all of the fingers may be provided with sub-fingers or lips 5 5 formed by stamping the metal as is shown. These lips may be bent outwardly at their free edges as shown at Fig. 4 so as to provide the inclined face 6 and abrupt face 7. When a finger 3 is inserted in a slot 2 the 10 lip 5 will be depressed by the action of this inclined face 6 against the edge of the slot 2 and the finger will freely enter the slot. As soon as it enters however the lip 5 will spring outwardly to its normal position and 15 in attempting to withdraw the finger 3 from the slot 2 will be prevented by the engagement of the abrupt face 7 of the lip 5 with the edge of the slot 2. This prevents accidental or unintentional displacement of the 20 parts. Should it be at any time necessary to disengage the ends of the sheet the lips 5 are held in depressed position while the fingers 3 are withdrawn from the slots 2.

In accordance with the present invention 25 the screen wall may be made of a number of sections, each section being provided with the locking means described and being locked to the adjoining section in the manner pointed out. The fingers of each section engage the slots of the next adjoining 30 section. When the required number of sections are locked together the entire screen is bent into annular form and the free ends of the end section are locked in the same 35 manner as described in a screen made of a single section. The screen made of a plurality of sections has the advantage that one small section may be replaced if damaged or worn without the necessity of renewing 40 the entire screen.

What I claim is:—

1. A screen for a centrifugal basket consisting of a sheet of material adapted to be bent into annular form, said sheet being 45 provided, adjacent one end, with a series of transverse slots, and being provided, adjacent the other end, with a corresponding series of inwardly pointing fingers adapted to enter into and be engaged by the transverse slots and means carried by said fingers for preventing their accidental withdrawal from the said transverse slots.

2. A screen for a centrifugal basket consisting of a sheet of material adapted to be bent into annular form, said sheet being provided, adjacent one end, with a series of transverse slots, and being provided, adjacent the other end, with a corresponding series of communicating transverse and longitudinal slits which form, in the body of 55 the sheet, a series of inwardly pointing fingers adapted to enter into and be engaged

by the transverse slots and means formed in said fingers for preventing their accidental withdrawal from the said transverse 65 slots.

3. A screen for a centrifugal basket consisting of a sheet of material adapted to be bent into annular form, said sheet being provided, adjacent one end, with a series of 70 transverse slots, and being provided, adjacent the other end, with a corresponding series of inwardly pointing fingers adapted to enter into and be engaged by the transverse slots, said fingers being provided with 75 members projecting from the plane surface thereof which permit such entrance but which resist withdrawal.

4. A screen for a centrifugal basket consisting of a sheet of material adapted to be 80 bent into annular form, said sheet being provided, adjacent one end, with a series of transverse slots, and being provided, adjacent the other end, with a corresponding series of inwardly pointing fingers adapted 85 to enter into and be engaged by the transverse slots, said fingers being provided with members each having an inclined face and an abrupt face, the inclined face permitting the entrance of the finger into the slot but 90 the abrupt face resisting withdrawal of the finger therefrom.

5. A screen for a centrifugal basket consisting of a sheet of material adapted to be bent into annular form, said sheet being 95 provided, adjacent one end, with a series of transverse slots, and being provided, adjacent the other end, with a corresponding series of communicating transverse and longitudinal slits which form, in the body of 100 the sheet, a series of inwardly pointing fingers adapted to enter into and be engaged by the transverse slots, the fingers being provided with communicating transverse and longitudinal slits which form, in the body 105 of the fingers, lips which permit entrance of the fingers into the slots but which resist withdrawal of the fingers therefrom.

6. A screen for centrifugals comprising a sheet of foraminous material provided near one end with a plurality of slots and near the other end with a plurality of corresponding struck-out, inwardly projecting fingers and the fingers provided with struck-out tangs, whereby the ends of the sheet may be connected by lapping the fingered end under the slotted end with the fingers in the slots and the struck-out tangs of the fingers bent backward to prevent accidental 115 removal of the fingers from the slot.

In testimony whereof, I have hereunto affixed my signature.

EDWARD N. STONE.
